FIG_1

FIG_2

FIG_5

FIG_3

FIG_4

FIG_6

FIG. 1 is a front, top and right side perspective view of a golf putter head showing my new design;

FIG. 2 is a top plan view;

FIG. 3 is a front elevational view;

FIG. 4 is a right side elevational view;

FIG. 5 is a left side elevational view; and

FIG. 6 is a bottom view.

The side opposite FIG. 3 is a mere image thereof.

The characteristic feature of my design resides in the combination of the two wood-grain inserts and the club head shown.

I claim:

The ornamental design for a golf putter head, as shown and described.
